UNITED STATES PATENT OFFICE.

HENRY L. WHITMAN, OF ST. LOUIS, MISSOURI.

BALING-PRESS.

No. 874,814.

Specification of Letters Patent.

Patented Dec. 24, 1907.

Application filed June 24, 1907. Serial No. 380,464.

To all whom it may concern:

Be it known that I, HENRY L. WHITMAN, a citizen of the United States of America, residing in the city of St. Louis and State of 5 Missouri, have invented certain new and useful Improvements in Baling-Presses, of which the following is a full, clear, and exact description, reference being had to the accompanying drawing, forming part of this specification.

10 My invention relates to a division block holder or dropper for presses for baling hay, cotton, excelsior and the like, and the object of my invention is to produce an article of 15 this kind which will be simple and effective in its operation and which will be inexpensive to manufacture and not liable to get out of order.

Figure I is a detail side elevation of a baling press with my improvement applied. Fig. II is a detail top view. Fig. III is a detail vertical section taken on line III—III, Fig. I. Fig. IV is a detail vertical section taken on line IV—IV, Fig. I.

25 Referring to the drawing: 1 represents part of the body of a baling press which may be of any well known form or type. Over the baling chamber of the press there is located the usual feed hopper 2 and the press 30 is provided with the usual feeder arm 3 having a projection 4 adapted to engage the division blocks when the latter are moved into position to enter the baling chamber of the press, such a feeder arm and projection being 35 old and well known.

5 represents a division block holder which is composed of channel bars 6 bolted or riveted to arms 7 that constitute a yoke or frame. The arms are bent inwardly from 40 the channel bars to a point 8 from where they project toward the power end of the press in the form of parallel extensions 9 that rest on a casting or bed 10 that has an upwardly inclined face 11, this bed being permanently 45 secured to the top of the frame of the press.

12 represents a lever pivoted at 13 to the casting 10 and at 14 to the extensions 9 of the yoke.

15 represents a brace secured at 16 to the 50 extensions 9 of the yoke and at 17 to a plate 18 that connects the channel bars 6 together at or near their upper ends. The channel bars are of sufficient width to receive a division block 19 and they have secured to 55 their lower ends flat springs 20 against which the division block rests until it is engaged by

the projection 4 of the feeder arm, when the springs will yield to the pressure and permit the division block to be moved into the baling chamber of the press.

60

The holder does not only serve to support and guide the division blocks but it also, serves the purpose of forming the end wall of the hopper so that as the holder is moved to its vertical position for the discharge of a division block it compresses the material longitudinally of the press so that when the feeder comes down, close up against the holder, the material will have been pressed well forward, the result being that there is no lap of 70 the material back of the point where it is engaged by the feeder arm. For the purpose of making a close fit between the flaring sides of the hopper and the division block holder I secure to the latter flaring end 75 pieces 21 that fit snugly against the inner faces of the sides of the hopper as shown in Fig. II, so that as the holder is moved forward by the lever 12 the material will be pushed ahead of it in good position to receive 80 the feeder when it descends and the block will move freely down into the baling chamber.

In operation the parts are in the position shown in Fig. I. When sufficient material, minus one charge, has been forced into the 85 baling chamber to form a bale, the lever 12 is moved from the position shown in full lines, Fig. I to the position shown in dotted lines, which brings the block holder and block into the position shown in dotted lines and the 90 feeder arm then automatically descending, presses the charge into the baling chamber and at the same time the projection 4 strikes the block and moves it into the chamber, the springs 20 yielding outwardly to permit the 95

passage of the block. As soon as the block has left the holder the lever 12 is thrown back to the position shown in full lines to permit another block to be inserted into the holder, the feeder arm automatically rises and when 100 the next charge is ready to be forced into the baling chamber the feeder is automatically moved but it does not now act upon the division block because the lever 12 has not been moved forward. This continues until 105 enough charges, minus one, have been introduced to form the next bale and then the lever is thrown forward so that the movement of the feeder arm to force the last charge of a bale into the baling chamber will also move 110 the division block into the baling chamber of the press.

It will be observed that the holder proper (that is the channel bars 6) have normally an incline position and that as the holder is brought to a position to drop the division blocks it moves both forwardly and to an upright position; that is, its movement is partly in a direction of the length of the press and partly in the arc of a circle so that the material is quite well condensed at the upper portion of the hopper, where it is usually the lightest, while at the lower portion of the hopper there is not so much compression of the material as to materially resist the movement of the holder in the operation of the lever 12.

15 The device is simple and inexpensive in construction, there is little or no danger of its getting out of order, and the introduction of the block into the baling chamber is positive and certain.

20 I claim:

1. In a baling press, a block holder or dropper, a yoke to which the holder is secured, a pivoted lever connected to the yoke, and a casting or stand to which the lever is pivoted and which has an inclined upper face upon which the yoke is adapted to bear, substantially as set forth.

2. In a baling press, a block holder or dropper consisting of channel bars adapted to receive a block and which are normally held in an inclined position, and means for moving the bars from such inclined position to a vertical position and at the same time move the bars forwardly so as to bring the block into position to be engaged by the feeder arm of the press, substantially as set forth.

3. In a baling press, a block holder consisting of channel bars adapted to receive the block, a yoke secured to the channel bars, an inclined bed upon which the yoke is adapted to bear when in normal position, and a lever pivoted to the bed and to said yoke; whereby, when the lever is operated the holder is moved forwardly and to an upright position, substantially as set forth.

4. In a baling press, a block holder consisting of channel bars having springs secured

to their inner lower faces, a yoke secured to the channel bars, an inclined bed upon which the yoke is adapted to rest to hold the channel bars in an inclined position normally, and a lever pivoted to the bed and to said yoke, substantially as and for the purpose set forth.

5. In combination with a baling press having a hopper with inclined side pieces, a block holder having wings fitting the inclined sides of the hopper, and means for moving the block holder forwardly and from an inclined to an upright position, substantially as set forth.

6. In combination with a baling press having a hopper with inclined sides, a block holder provided with wings adapted to fit the inclined sides of the hopper, a yoke secured to the holder, an inclined bed upon which the yoke rests normally, and a lever pivoted to the bed and to said yoke, substantially as set forth.

7. In combination with a baling press having a feed hopper, a block holder located between and within the sides of the hopper, and adapted to form one end of the hopper, and means for moving the holder in a forward direction, substantially as set forth.

8. In combination with a baling press having a feed hopper, a block holder adapted to form one end of said hopper and which is held in an inclined position normally, and means for moving the block holder forwardly and to an upright position, substantially as set forth.

9. In combination with a baling press having a feed hopper, a block holder consisting of channel bars provided with wings adapted to fit against the inner faces of the sides of the hopper, a yoke secured to the channel bars, an inclined bed against which the yoke is adapted to rest when in normal position, and a lever pivoted to the bed and to said yoke, substantially as set forth.

HENRY L. WHITMAN.

In presence of:

LILY Post,
Wm. H. SCOTT.
